UNITED STATES PATENT OFFICE.

WILLIAM R. BASSETT, OF NEW YORK, N. Y., ASSIGNOR TO SACKS & BROTHER, OF SAME PLACE.

DESIGN FOR FRINGE.

SPECIFICATION forming part of Design No. 14,014, dated July 3, 1883.

Application filed April 19, 1883. Term of patent 7 years.

To all whom it may concern:

Be it known that I, WILLIAM R. BASSETT, of the city and State of New York, have invented a certain Design for Upholstery-Fringe, 5 of which the following is a specification.

The design of this fringe is represented in the accompanying drawing.

I employ cords *a b*, with intermediate tufted strip, *c*, and smaller interlacing cords, *d*, as 10 represented. The pendants of the fringe are composed of the chenille or tufted balls *e*, molds *f*, tapering chenille bodies *g*, and bottom ornaments, *h i*, substantially as specified and shown.

15 This design is highly ornamental and artistic in appearance. The chenille is represented as mottled, but this is not essential to the design; and the covering-bands *o* of the molds *f* are also represented as mottled and glittering, 20 but these bands may be plain.

This design is to be distinguished from the fringe heretofore made, in which there are worsted tassels with the fibers looped at the head and hang down loosely, in place of the chenille drops, the artistic appearance of the 25 latter being different from the worsted.

I claim as my invention—

The design of the ornamental fringe, consisting in the head-piece, with cords *a b*, intermediate tufted strip, *c*, pendants with balls 30 *e*, molds *f*, tapering chenille bodies *g*, and bottom ornaments, *h i*, substantially as specified and shown.

Signed by me this 3d day of April, A. D. 1883.

WM. R. BASSETT.
